UNITED STATES PATENT OFFICE

96,286

DESIGN FOR A GLIDER

John Carlton Ward, Jr., Rome, N. Y., assignor to
The Rome Company, Inc., Rome, N. Y., a cor-
poration of New York

Application March 8, 1935, Serial No. 55,782

Term of patent 14 years

To all whom it may concern:

Be it known that I, John Carlton Ward, Jr., a citizen of the United States, residing at Rome, in the county of Oneida and State of New York, have invented a new, original, and ornamental Design for Gliders, of which the following is a specification, reference being had to the accompanying drawing, forming part thereof, in which

Fig. 1 is a perspective view of the glider showing the design; and

Figs. 2 and 3 are perspective views of the end

member thereof showing the straight top and curved base of the end member.

A feature of the design is the provision in a glider of end members each presenting a continuous outwardly curved surface which merges from a substantially straight edge at the top of each member to a curved edge at the floor line.

I claim:

The ornamental design for a glider as shown and described.

JOHN CARLTON WARD, Jr.
